CLAIM

The ornamental design for a cup warmer, as shown and described.

DESCRIPTION

FIG. 1 is a first perspective view of a cup warmer showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1;

FIG. 10 is an enlarged view of the selected portion 10 in FIG. 1; and,

FIG. 11 is an enlarged view of the selected portion 11 in FIG. 2.

The broken lines shown in the drawings depict portions of the cup warmer that form no part of the claimed design. The dot-dash broken lines represent the designation of the enlargement views and form no part of the claimed design.

1 Claim, 11 Drawing Sheets
